CLAIM

The ornamental design for a shoe welt, as shown and described.

DESCRIPTION

FIG. 1: is a front perspective view of the shoe welt showing my new design.

FIG. 2: is a front elevation view thereof.

FIG. 3: is a rear elevation view thereof.

FIG. 4: is a left side elevation view thereof.

FIG. 5: is a right side elevation view thereof.

FIG. 6: is a top plan view thereof; and,

FIG. 7: is a bottom plan view thereof.

The broken line showing the remainder of the shoe represents environmental subject matter that forms no part of the claimed design.
